[57] CLAIM

The ornamental design for an anti-aging pillow, as shown and described.

DESCRIPTION

FIG. 1 is a top, left front perspective view of an anti-aging pillow showing my new design;

FIG. 2 is a right side elevational view thereof, the left side being a mirror image thereof;

FIG. 3 is a top front perspective view of a second embodiment of my design of FIG. 1;

FIG. 4 is a front elevational view of FIG. 3, the rear view being identical thereto; and,

FIG. 5 is a top plan view of FIG. 3, the bottom plan view being a mirror image thereof.
